United States Patent Office.

P. L. SLAYTON, OF NEW YORK, N. Y., ASSIGNOR TO HIMSELF AND ALMET REED, OF SAME PLACE.

Letters Patent No. 65,699, dated June 11, 1867.

IMPROVED APPARATUS FOR TEMPERING WIRE.

The Schedule referred to in these Letters Patent and making part of the same.

TO ALL WHOM IT MAY CONCERN:

Be it known that I, P. L. SLAYTON, of the city, county, and State of New York, have invented a new and improved Machine for Tempering Wire; and I do hereby declare that the following is a full, clear, and exact description thereof, which will enable others skilled in the art to make and use the same, reference being had to the accompanying drawings, forming part of this specification.

This invention relates to a new and improved machine for tempering wire, and is more especially designed for tempering wire braces for umbrellas and parasols, and straightening the same during the process of tempering. In the accompanying sheet of drawings—

Figure 1 is a side view of my invention.

Figure 2, a longitudinal section of the same taken in the line *x x*.

Figure 3, an end view of the same.

Figure 4, a transverse section of the same taken in the line *y y*, fig. 1.

Similar letters of reference indicate like parts

A A represent two standards, in the upper parts of which there are fitted cylindrical heads, B B', having each a central hole, *a*, through it. In the inner sides of these heads there are circular recesses or chambers to receive the ends of four bars C, each of which is a longitudinal quarter of a cylinder, as shown in fig. 4. The ends of the bars C are secured in the recesses or chambers in the heads B B' by means of screws D. The bars C are not in close contact. Spaces are allowed between them to receive strips or bars, E, of metal, the inner ends of which are of V-form, as shown clearly in fig. 4. These strips or bars are adjustable, that is to say, may be raised higher or lower in the spaces between the bars C by means of screws F F', the screws F being secured in the strips or bars E, passing through the sides of B B', and having nuts *b* on their outer ends, the screws F' passing through curved metal bars G, which are attached to the exterior of the bars C by screws D', and bear upon the outer edges of the strips or bars E. By this means the strips or bars E may be adjusted further inward or outward and secured at any desired point, so that a greater or less space may be allowed between their inner ends, as desired. The strips or bars E have each a hole, *c*, extending longitudinally through them, and these holes *c* communicate, by means of small perforations, *d*, with longitudinal recesses *e* in the bars C, the recesses *e* extending the whole length of C and nearly to the inner ends of the same, and having holes, *f*, at their bottoms or inner ends, the holes *f* being much larger in diameter than the perforations *d*, but in line with the same. Besides these large holes *f*, the recesses *e* have small perforations, *g*, made through their inner ends, which are in line with the spaces between the strips or bars E, as shown in figs. 1, 2, and 4. The head B has a groove or recess, *h*, made in its periphery and extending entirely around it. This groove or recess is enclosed by the standard A, in which the head B is fitted, and communicates by passages *i* with the holes *c* in the strips or bars E, as shown clearly in fig. 2. H is a pipe, which communicates with the recess *h*, and through which gas is conducted into *h*, and from thence into the holes *c* in the strips or bars E, the gas passing from *c* into the perforations *d*, at the outer orifices of which it is burned, as shown clearly in fig. 4, the inner portions of the jets being within the recesses *e* of the bars C, as shown in fig. 4. The perfect combustion of the gas is insured by the admission of air to the same through the holes *g*, the air passing into the latter from the spaces between the inner ends of the strips or bars E. The gas-jets heat the bars C and the strips or bars E, and, if necessary or desired, the device may be enclosed within a jacket in order to prevent the radiation of heat. The wires *a*, shown in red, are previously tempered as hard as possible in the usual way, and are then reduced or brought down to a spring or blue temper by inserting them, one at a time, in the opening between the inner ends of the strips or bars E, the wires being straightened in passing between the inner edges of the bars or strips. The strips or bars E are adjusted further in or out so as to regulate the size of the opening between their inner edges to suit the thickness of the wire to be tempered. Several of these devices are to be used by one operator at the same time in order that no time may be lost, as each wire requires to be left in a device sufficiently long to have the temper reduced to the proper degree. One operator would require about five or six of the devices in order that he may be kept constantly at work.

Having thus described my invention, I claim as new, and desire to secure by Letters Patent—
The radially adjustable strips or bars E, arranged between the guide-bars C, and provided with holes or gas passages e, communicating with recesses e in the guide-bars C, all arranged substantially in the manner as and for the purpose set forth.

I also claim the central passage formed by the strips or bars E of such a size as to receive the wire to be tempered, and to permit a current of air to pass to the gas-jets, and this I claim whether said strips E are adjustable or stationary.

P. L. SLAYTON.
